BUILDING CONSTRUCTION

Original Filed June 10, 1929

UNITED STATES PATENT OFFICE

FREDERICK M. VENZIE, OF PHILADELPHIA, PENNSYLVANIA

BUILDING CONSTRUCTION

Original application filed June 10, 1929, Serial No. 369,537. Divided and this application filed December 20, 1929. Serial No. 415,522.

This invention, generally stated, relates to a building structure and has more especial relation to a wall, ceiling, and partition construction.

5 An object of the present invention is to provide plaster boards in connection with metal beams or girders so that metal clips of special design may be employed for securing the plaster boards in place.

10 Another object of the present invention is to so construct the plaster boards that relatively tight joints are effected between adjacent plaster boards when the metal clips are positioned.

15 Another object is to provide a special form of plaster board having end portions arranged to straddle a pair of beams, or girders, to provide a sound deadening partition between adjacent beams or girders.

20 A further object resides in the provision of a clip for holding plaster boards in place, which clip is provided with a slot and oppositely turned prongs whereby the clip may be fitted to a channel iron to retain its position without the employment of fastening mediums.

25 Other and further objects reside in the provision of general details of construction and in the arrangement, combination, and connection of parts for attaining the results sought by the foregoing objects.

30 The invention consists of the novel construction hereinafter described and finally claimed.

35 The nature, characteristic features and scope of the invention will be more fully understood from the following description taken in connection with the accompanying drawings forming part hereof, and in which:

40 Fig. 1 is a fragmentary view in sectional plan illustrating the manner of arranging a sound deadening plaster board between a pair of channel irons.

45 Fig. 2 is a view in vertical section of the left hand side of Fig. 1.

50 Fig. 3 is an enlarged sectional view of one of the plaster boards seen in Fig. 2 and taken upon the line 3—3 of Fig. 7.

55 Fig. 4 is a view in perspective of one of the clips shown in Fig. 2.

Fig. 5 is a front elevation of the same.

Fig. 6 is a sectional view taken upon the line 6—6 of Fig. 7;

Fig. 7 is a plan view of the plaster board shown in Figs. 3 and 6; and

Fig. 8 is a top or plan view of the clip shown in Fig. 4.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the 70 reference numeral 1 designates a pair of channel irons vertically arranged to support side walls or partitions formed of plaster boards.

2. These plaster boards are provided with a paper covering. In practice a long length 75 of plaster board is formed and then cut into desired sizes. Upon the sides or uncut portions of a section, see Figs. 3 and 7, I extend the paper covering to provide somewhat coiled portions 3. At the opposite ends of a 80

plaster board, that is the cut off ends, I attach, as by glue, members 4 of substantially circular cross section, see Figs. 6 and 7. The purpose of these cushion-like parts is to provide a relatively tight joint between adjacent 85

plaster boards when clamped together so that the penetration of sound is retarded as much as possible. The clips which are employed for securing the plaster boards 2 to the channel irons are best seen in Figs. 4 and 90

5. They are of metal and are stamped from a single blank. Each clip comprises a ledge 5, slotted at 6, which slotted portion has arranged immediately adjacent thereto prongs 7 and 8 which are at an angle with respect to 95

the ledge 5. These prongs are extended in opposite directions. At each end of ledge 5 are a pair of lips 9 and 10 and arranged centrally of the ledge is a single lip 11. In practice the prongs 7 and 8 are shaped around a 100

10

channel iron 1 and a pair of plaster boards 2 fitted to place upon opposite sides of the ledge 5 with one board fitted between the lips 9 and 10 and the other board abutting against lips 11 upon one face and having its other face abutting against channel iron 1. This makes a very efficient and rigid connection of parts, and with the coil like ends 3 of a board squeezed between the meeting edges of the boards a sealing effect is obtained. After the plaster boards 2 are positioned a coating of plaster 12 is applied, as usual. Between adjacent channel irons or beams 1, I arrange plaster boards 13 which are thicker than the boards 2 and are cut out at their opposite ends to engage around the channel irons, as best seen in Fig. 1. Each plaster board 13 is provided with a pair of openings 14 through which wires 15 may be introduced and tied around the channel irons 1 to secure the plaster boards 13 in place. These plaster boards 13 assist in rendering the entire structure more sound resisting. While I have described oppositely disposed prongs 7 and 8 adjacent the single slot 6, I may dispense with one of said prongs and employ a single prong arranged substantially in parallelism with the ledge 5 and slot 6 to engage with an edge of the channel iron 1. Also the lips 10 may be omitted and the remaining lips 9 and 11, which are arranged at right angles to the ledge 5, may be employed to abut against and support the face portions of the plaster boards when the end portions of the plaster boards abut against the opposite sides of the elongated, narrow, flat ledge 5.

What I claim is:

1. A clip for use in building construction, comprising a one piece metallic member having a ledge struck out from which are inclined prongs arranged at an acute angle with respect to said ledge and to one another for engaging around a channel iron, opposed lips extended outwardly from said ledge to receive a plaster board, and a single lip extended from the side of said ledge opposite said inclined prongs and arranged intermediate the opposed lips.

2. A clip for use in building construction, comprising a one piece metallic member having a ledge struck out from which are prongs arranged at an angle with respect to one another for engaging around a channel iron, opposed lips extended outwardly from said ledge to receive a plaster board, the terminals of said lips being outwardly flared and slightly rounded, and a single lip extended from the opposite side of said ledge and arranged intermediate the opposed lips.

3. A clip of the character stated comprising a one piece metallic member having an elongated ledge, inclined prongs struck out from said ledge and arranged at an acute angle with respect to said ledge and to one another and extending in different horizontal planes

for engaging a channel iron flange, opposed lips of U-shaped cross-section extended from one side of said ledge to receive a plaster board, and a single relatively broad lip extended from the opposite side of said ledge and arranged intermediate said U-shaped lips.

4. A clip of the character stated comprising a one-piece metallic member having an elongated, narrow, flat, plate-like body arranged to have plaster board end portions abut against opposite faces of said body, said body being slotted in the direction of its length to form a hook-like prong for engagement over the flange of an angular beam, which prong parallels said slot, said body having struck out and extended from at least one end thereof a prong arranged substantially in parallelism with said body and slot for engagement with a channel iron edge, and a plurality of fingers struck out and extended from said body at right angles thereto to receive and abut against the opposed faces of a plaster board.

In testimony whereof, I have hereunto signed my name.

FREDERICK M. VENZIE.
